Primary Examiner — Cynthia Ramirez

(57) **CLAIM**

The ornamental design for a composter, as shown and described.

DESCRIPTION

FIG. 1 is a rear and bottom perspective view of a composter, showing my new design;

FIG. 2 is a front and top perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of the portion, labeled '9' of FIG. 2.

The dash-dot broken lines in FIGS. 2 and 9 are to show enlarged areas and form no part of the claimed design.

1 Claim, 9 Drawing Sheets(56)
